UNITED STATES PATENT OFFICE.

HENRY H. CUMMINGS, OF MALDEN, ASSIGNOR TO THE UNION BUTTON SEWING MACHINE COMPANY, OF BOSTON, MASSACHUSETTS.

STOP-MOTION MECHANISM FOR SEWING-MACHINES.

SPECIFICATION forming part of Letters Patent No. 391,769, dated October 23, 1888.

Application filed May 6, 1887. Serial No. 238,001. (No model.)

To all whom it may concern:

Be it known that I, HENRY H. CUMMINGS, of Malden, in the county of Middlesex and State of Massachusetts, have invented certain new and useful Improvements in Stop-Motion Mechanisms for Sewing-Machines, of which the following is a specification.

My invention relates to sewing-machines of the class employing devices for automatically arresting the operation of the main shaft after a predetermined number of revolutions thereof have been made.

It is the object of my invention to provide simple and efficient mechanism for accomplishing the purposes mentioned, located with in the standard or support for the overhanging arm, where it may be near to the clutch mechanism, convenient of access, and at the same time be out of the way of danger of damage by contact with other things or parts of the machine, as will be hereinafter fully and clearly set forth, and particularly pointed out in the claims.

Of the drawings hereto annexed and forming a part of this specification, Figure 1 represents a perspective view of my invention, only so much of a sewing-machine frame being shown as is necessary to illustrate the relationship or connection of my improvements therewith. Fig. 2 is a rear elevation of the same. Figs. 3 and 4 are sectional views on the line *z z* of Fig. 2, looking in the direction of the flight of the arrow marked thereon, showing the parts in different positions. Fig. 5 is a front elevation of portions of the machine pictured in Figs. 1 and 2, showing my improvements as applied thereto. Figs. 6 and 7 are sectional views on the line *3 3* of Fig. 5, looking in the direction of the flight of the arrow pictured thereon, and showing the parts there represented as in different positions and corresponding to the positions portrayed in Figs. 3 and 4.

Similar letters of reference indicate similar parts in all of the figures.

A represents the bed of the machine; B, the overhanging arm; C, the standard supporting the same; D, the main driving-shaft, and E the driving-pulley, adapted to receive a

band to rotate shaft D and operate the machine.

The parts just described may be of the form represented or of any other form common in the construction of sewing-machines.

The driving-pulley E is adapted to turn loosely on shaft D, but is constructed to be connected therewith by means of pins or lugs F, projecting laterally from the pulley coming in contact with a clutch-dog, G, swiveled or pivoted to shaft D, as most clearly represented in Figs. 6 and 7. The outer end of the clutch-dog G is normally held pressed toward the adjacent face of the pulley by means of a spring, H, surrounding the pivot-pin I.

J represents a lever pivoted at K to the standard C, and having a portion, L, bent at right angles thereto, and extending behind or along the rear of the standard, to which angular portion is attached a finger, M, extending forward and upward, and—when raised by the lever—into the path of travel of the outer end of dog G, so that said dog may engage the inner inclined face of said finger and be drawn back from engagement with the lugs F, and thus unclutch pulley E from the driving-shaft and stop the machine.

The mechanism thus far described, except as to the lever J and to the relationship to other devices, is not essentially different from that shown and described in the patent granted to Driscoll, December 16, 1884, No. 309,209, to which patent reference may be had.

Angular part L of lever J has a cam piece or block, a, formed on or connected therewith, having an inclined face, 4, and an angular point or projection, 5, as shown in Figs. 1, 6, and 7.

b indicates a latch-lever pivoted at its lower end, as at c, to the standard C, and having the outer end of a tripping-arm, d, extending through and a short distance beyond to its upper free end, (see Figs. 1, 2, and 5,) which projecting end d' of tripping-arm d is adapted to rest on cam-piece a, and as the latter is moved ride up its inclined face 4 and be caught or locked on the angular point or projection 5, as seen in Fig. 6. Tripping-arm d extends horizontally through the rear of standard C,

downward, and again horizontally outward within said standard, where a plate, *e*, is secured thereto, which plate is provided with laterally-projecting fingers *f g*, for a purpose 5 to be presently explained.

h indicates a lever pivoted on a stud, *i*, to the inner forward side of standard *C*. Said lever *h* is bifurcated or forked at its upper end, so as to embrace a cam, *j*, on main shaft *D*, 10 and be thereby rocked on its pivot *i*. A pawl, *k*, is pivoted on the lower end of lever *h* and adapted to engage the teeth of ratchet-wheel *l*, adapted to turn loosely on stud *i*. Said ratchet-wheel is provided with holes *m*, 15 responding in number and position with the teeth of the wheel, which holes are adapted to receive a laterally-projecting pin or stud, *n*, of a lug or dog, *o*, and so be fixed at any desired point on said wheel.

20 *p* represents a holding-pawl pivoted to stud *P* on the side of standard *C*, and arranged to engage the teeth of ratchet-wheel *l* and hold the same from turning backward, or in a direction opposite to the arrow marked thereon, 25 when an intermittently rotary movement is being imparted to the ratchet-wheel by the operation of pawl *k*. Springs *q r*, respectively coiled about and secured to the pivotal studs and bodies of pawls *k* and *p*, respectively operate with a tendency to hold said pawls in engagement with the teeth of ratchet-wheel *l*.

20 Finger *f* of plate *e* extends out alongside of and in contact with the lower end or tail of pawl *p*, and the tail or rear end of pawl *k* rests against the front cam-shaped face of the tail of pawl *p*. Finger *g* of said plate *e* extends laterally into the path of travel of lug or dog *o*.

40 The operation of my invention may now be described as follows: Supposing the normal position of ratchet-wheel *l* to be that represented in Fig. 4, and the dog *o* to be fixed thereon, as pictured in said last-mentioned

45 figure, the machine may be set in operation by raising the handle of lever *J*, which will depress finger *M* and allow one of the studs *F* on pulley *E* to come in contact with dog *G* and so rotate the main shaft. When finger *M*

50 was depressed, as just explained, the upper end of locking-lever *b* was carried backward in the direction of the arrow marked thereon from the position represented in Fig. 7 to that portrayed in Fig. 6, and the projecting end *d'* 55 of tripping-arm *d* brought over the point or corner 5 of cam-piece *a*, whereby said finger *M* is locked in its depressed position. This movement of locking-lever *b* is accomplished partly by the tension of the springs *q* and *r*

60 of pawls *k* and *p* operating through said pawls on finger *f* of plate *e*, secured to tripping-lever *d*, and partly by the mere gravity of said lever *b*. By the movement also just described plate *e* on tripping-lever *d* was brought into 65 position represented in Fig. 3, so as to permit pawls *k* and *p* to engage the teeth of ratchet-wheel *l*, and the latter be rotated or

70 moved one tooth at each rotation of main shaft *D*, through the medium of cam *j*, lever *h*, and pawl *k*, and this operation will continue until dog *o* is brought into contact with finger *g* of plate *e*, as represented in Fig. 3, when at 75 the next movement of the ratchet-wheel said dog will draw back said finger and throw the projecting end *d'* of tripping-arm *d* off point 80 5 onto incline 4 of cam-piece *a*, when, by the action of spring *r'* operating on the end of lever *L* to draw it upward, said inclined face 4 of cam-piece *a* will throw locking-lever *b* back in a direction opposite to the flight of the arrow, carrying finger *f* down against and so as to throw forward the tail of pawl *p*, which will at the same time be brought into contact with the tail of pawl *k*, and both pawls thus thrown out of engagement with the ratchet-wheel *l*. The pawls *k* and *p* being thus freed from the teeth of ratchet-wheel *l*, the latter is returned to its normal position (see Fig. 4) by the action of a "watch-spring," *s*, (shown in dotted lines in Figs. 3 and 4,) coiled around 90 stud *i* on the inner side of ratchet-wheel *l*, and having one end secured to said stud and the other end to said ratchet-wheel.

95 In Figs. 1, 3, and 4 portions of two teeth of ratchet-wheel *l* are cut away in such manner as, while not affecting the functions of holding-pawl *p*, (which is wider than pawl *k*, extending across the entire width of the ratchet-wheel,) to render inoperative and ineffectual the movement of pawl *k* when they arrive 100 opposite thereto, (which is as far as the ratchet-wheel can with safety be turned,) thus preventing breakage of any of the parts connected with the ratchet-wheel in case the pawls are not tripped and the machine is left running. This mutilation of the teeth of ratchet-wheel *l* is done for the purpose of providing 105 against the further turning of said ratchet-wheel in the event of a failure from any cause in the operation of the tripping devices, and so avoid the breaking of spring *s* or other parts of the machine.

When lever *J* was released and angular part *L* drawn upward by spring *r'*, as has been described, finger *M* was also drawn upward into 110 the path of travel of dog *G*, which latter device, coming in contact with the inner inclined face of said finger, was drawn away from contact with studs *F* on pulley *E*, permitting said pulley to run free on shaft *D*, the engagement 115 of dog *G* with finger *M* stopping the rotation of said shaft.

120 By the construction and arrangement of parts described a very simple, compact, and effective stop-motion mechanism for sewing-machines is provided, and by locating it within the standard of the overhanging arm it is placed out of the way of liability of damage by contact with other things, space not otherwise occupied is utilized, and it is at the same time 130 made convenient of access.

125 It is obvious that the form and arrangement of parts comprising my improvements may be varied within the limits of mechanical skill

without departing from the spirit or nature of the invention.

Having thus described my invention, what I claim is—

5 1. The combination, with the main shaft, its driving-pulley, and the dog engaging lugs of said driving-pulley, of the hollow standard and arm, the lever fulcrumed on said standard, and having a right-angular end provided 10 with a cam piece or block, *a*, the finger connected to said lever, the tripping-arm engaging said cam piece or block, and the tripping mechanism connected to said tripping-arm, which, together with said tripping mechanism, is located in said hollow standard, substantially as shown and described.

2. The combination, with the main shaft, its driving-pulley, and clutch mechanism for connecting the driving-pulley with and disconnecting it from the main shaft, of the lever *J*, having the right-angular end provided with a cam piece or block, *a*, the finger connected to said lever, the latch-lever *b*, the tripping-arm connected at one end to said latch-lever, the plate *e*, having the fingers *f g*, the main shaft having the cam secured thereon, the lever operated by said cam, the pawl pivoted to and operated by said lever, the ratchet-wheel, with which said pawl is adapted to engage, a hold-

ing-pawl, also adapted to engage said ratchet-wheel, and a dog on said ratchet-wheel adapted to be brought into contact with one of the fingers of said plate *e*, as set forth.

3. The combination, with the main shaft carrying a cam, the driving-pulley, the clutch mechanism for connecting the driving-pulley with and disconnecting it from said main shaft, the lever having a right-angular end provided with a cam piece or block, and the tripping-arm having the plate *e*, provided 40 with two fingers, *f g*, of the ratchet-wheel having a series of holes, *m*, and secured on a stud, *b'*, the lug or dog *o*, having a laterally-projecting pin or stud, *n*, designed to enter one of said holes, the coil-spring secured to said ratchet-wheel and to the stud *b'*, the lever *h*, having the upper bifurcated end, the pawl pivoted to and operated by said lever, and the holding-pawl adapted to engage said ratchet-wheel, substantially as shown and described.

In testimony whereof I have signed my name to this specification, in the presence of two subscribing witnesses, this 11th day of April, A. D. 1887.

HENRY H. CUMMINGS.
